UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

PUMP MECHANISM FOR STEREOGRAPH-PRINTING-PLATE-CASTING MACHINES.

1,259,947.

Specification of Letters Patent. Patented Mar. 19, 1918.

Original application filed January 12, 1910, Serial No. 537,700. Divided and this application filed September 4, 1915. Serial No. 48,984.

To all whom it may concern:

Be it known that I, HENRY A. WISE Wood, a citizen of the United States, residing at New York, in the county of New York and State of New York, have invented a new and useful Pump Mechanism for Stereotype-Printing-Plate-Casting Machines, of which the following is a specification.

This is a division of my application Serial No. 537,700, filed Jan. 12, 1910, patented December 14, 1915, No. 1,164,607.

Among the objects of the invention are to provide a melting pot having a recess to contain the pump so as to overcome the pull due to contraction of the body of the metal in the pot due to cooling; to provide means for operating the pump valve so that it shall be automatically closed by the first part of the upward movement of the pump plunger unless it is held open by means controlled by the matrix or dummy matrix; to provide means whereby if one or more of the matrices or dummy matrices have their corners cut away under the pump valve trip device, the pump valve will remain open and no plates will be cast; and to provide a mold adapted to be resiliently held against the pump nozzle to allow of expansion and contraction of the parts so as to keep the mold and pump nozzle in proper relation to each other, thereby preventing leakage of metal. The invention also involves improvements in various details of construction as will appear hereinafter.

Reference is to be had to the accompanying drawings, in which—

Figure 1 is a plan of a pump for a flat stereotype plate casting machine constructed in accordance with this invention;

Fig. 2 is a side elevation of the same with parts removed;

Fig. 3 is a sectional view on the line 3—3 of Fig. 1;

Fig. 4 is a section of a detail;

Fig. 5 is an end view of the mold, partly in section;

Fig. 6 is a longitudinal sectional view of the melting pot and casting pump showing other features in elevation; and

Fig. 7 is an elevation of the casting mouth thereof.

This invention is shown in a form for casting stereotype plates and as embodying

a frame 3 having means for supporting various parts of the machine. A longitudinal shaft 4 is shown at the front side of the machine, which can be called the driving shaft. 55

A reciprocating supporting plate 91 is mounted to move in vertical guides 92 on the frame, and carries the lower casting box 93. The supporting plate 91 is raised by a cam 6 on the shaft 4 which operates an arm 7 pivoted on a bracket and provided with a connecting rod 8 extending back toward the center of the machine. With this latter rod is pivotally connected an arm 9 on a rock shaft 10 which is provided with another arm 11, these parts constituting in effect a bell-crank. The arm 11 is pivotally connected with a connecting rod 12 which is pivoted to the bottom of the plate 91. On the frame is mounted a bracket 13 provided with an adjustable stop 14 for limiting the motion of the connection between the parts 11 and 12 and preventing them from going too far beyond the center. 65

The upper casting box 95 is supported on two brackets 20 on which are standards 21 carrying rods 22 and 32. The upper box is supported from the rods by plates 23. On the rods are springs 23* bearing on the plates 23 nearest the melting pot, and on collars 15 fixed to the rods. These springs obviously tend to keep the upper box yielding against the nozzle. The lower box 93 is held up against the nozzle by a spring 16 operating a rock shaft 17 which is provided with an arm 18 engaging the end of the box. This allows for expansion and contraction and keeps the boxes in proper relation to the pump nozzle so as to prevent leakage. 85

Through the bases of the plates 23 pass thimbles 19 which extend slightly below the bottom thereof. A bolt 24 extends through each thimble and these bolts fasten the upper box to the standards 21. The thimbles rest on the distance piece 33 by which the elevation of the upper box is controlled. 95 This construction permits the springs 23* to keep the upper box up against the nozzle. The rod 22 rests in open slots on the brackets 21. 100

Mounted in a vertical guide 25 on the upper section of the casting box is a pin 26

which projects down through into the casting box so that as the lower section of the box moves up, if the matrix M is in position, the matrix will engage the bottom of the 5 pin and raise it enough to move an arm 27 which is mounted on a rock shaft 28. If, however, the corner of the matrix or dummy matrix is cut away, the parts can be moved up into casting position without 10 moving the pin so that this shaft will not be operated. When this shaft is turned by the proper closing of the box containing a complete matrix and adapted to receive metal, this causes a latch 29 thereon to be 15 moved from the path of the top of a vertical rod 30 having a valve 31 thereon; but if the parts operate with a dummy matrix in position which has the rear left-hand corner cut away, the latch 29 will remain over the 20 top of the rod 30 and hold the latter down. The object of this construction will be seen from the following description of the operation of the pump.

On the shaft 4 is a cam 40 operating a 25 roller 41 on a spring pressed arm 42 which is fixed on a rock shaft 43. This rock shaft operates an arm 44 which reciprocates a pump plunger 45 in a melting pot 46. This plunger is mounted in an open-bottomed 30 cylinder 47 submerged in the pot and the cylinder is located in a recess within a perforated wall 48 in the pot to protect the pump against the tension or pull due to the contraction of the body of metal in the pot 35 upon cooling. Now each rotation of the cam 40 will move the plunger through a complete reciprocation in the pump cylinder. The upward reciprocation of the plunger will force metal upwardly through 40 the nozzle 49 into the mold unless the valve 31 is held down by the latch 29 as above explained. Then the reciprocation of the plunger will only cause a circulation of the metal in the pump up through the passage 45 50 which the valve 31 controls.

It will be seen therefore, that the pump valve 31 is closed by the first part of the upward movement of the pump plunger on account of the tendency of the metal raised 50 thereby to flow out of the opening 50 unless the valve is held down by the latch, so that if one or more of the matrices or dummy matrices in the mold have their corners cut away all the parts of the pump will operate but the metal will not be forced into the casting box.

If it is desired to keep the valve 31 down all the time so that no metal can be forced from the pump, as for instance while re- 60 pairing machinery, the rock shaft 28 is turned to bring a catch 52 over a fixed collar 53 on the rod 30. This can be done by pulling up on the arm 27 when in the position shown in Figs. 2 and 5. The parts will 65 remain in this position and the machine can

be operated without danger of flooding the parts with metal.

The nozzle of the pump is provided with a slot 55 of a width in proper proportion to the width of the mold cavity in the casting box. The height of the slot is regulated by the position of a top part 56 held in an adjustable position by bolts 57 passed through elongated orifices therein. Both the top and bottom members of the end of the nozzle are shown as cooled by air passing through passages 58. This is provided to cause the metal to chill at the proper place between the plate and the body of metal left in the nozzle.

8-

An arm 64 is keyed on the shaft 43 and connected with the lever 44 by a pin 62 at a distance from the point at which the latter is freely pivoted on the shaft. This pin is provided with a reduced cross section so that in case of any obstruction to the proper operation of the machine sufficient to cause breakage, the breakage will occur at this point. In this case the breaking point is located between the end of the arm 64 and 90 a boss 65 on the lever 44.

85

When the casting boxes close another plate will be cast from the same matrix unless another one or a dummy is fed into the lower casting box while in lowest position. In that case the old matrix will be forced out of the box by the rear matrix 95 guided by the end gages and drop at the rear of the frame.

95

When it is desired to operate the machine 100 one or a definite number of times without casting a plate, one or more dummy matrices with their corners cut away are placed in the mold under the end gages which hold its edges on the lower casting box. Then the 105 latter rises, lifts the top section a very slight distance and brings the parts into registration with the nozzle ready for the casting of a plate. At this time the spring 60 has brought the rock shaft 43 around 110 into such position as to raise the plunger in the pot, which closes the valve and thus forces the metal into the casting box, with a yielding pressure. The spring continues to exert a pressure on the plunger while the 115 metal is cooling in the mold to compensate for the contraction of the metal. The cams have sufficient dwell at this point to allow the casting box to remain closed long enough to allow the plate to harden. Then 120 the lower box moves down. The upper box remains substantially in the first position. The way in which the pump is prevented from operating is exceedingly simple and effective and of course results in allowing 125 the other operations of the machine to take place without casting a plate, as for example, at the end of any continuous casting operation a dummy would be introduced so as to permit the last matrix to be delivered. 130

The various mechanisms are adjustable in all necessary ways to take care of plates of different sizes.

While I have illustrated and described a 5 preferred embodiment of the invention and shown it as applied to the casting of flat printing plates, I am aware that many modifications can be made in the various details of construction and the sequence of 10 operations and that most of the parts can be employed for casting stereotype plates, and in fact other articles, of different shape and character from the plates specified. Therefore, I do not wish to limit myself to 15 the details of construction or sequence of operations or shape of plates described herein, but what I do claim is:—

1. In a stereotype plate casting machine, the combination of a pump, a lever for operating the pump, a rock shaft on which said lever is loosely pivoted, and an arm fixed on said rock shaft, and a pin connected with said arm and with said lever at a distance from the rock shaft, said pin having a reduced cross-section.
2. In a melting pot and pump, the combination of a pump cylinder, and a wall in the pot protecting the pump cylinder from contraction of the metal.
3. In a melting pot and pump, the combination of a pump cylinder, a piston, and

a wall in the pot surrounding said cylinder and piston and having perforations through the bottom thereof for overcoming the pull due to the contraction of the body of metal 35 in the pot by cooling.

4. In a melting pot for casting purposes, the combination of a pump having a nozzle provided with a long narrow slot, and a plate forming the upper boundary of the 40 slot adjustable in a direction transverse to the long dimension of said slot.

5. The combination of a pump comprising a piston, a cylinder, and a valve, said valve being in position to be closed by the 45 working stroke of the piston and to render the pump inoperative when held open, means adapted to hold the valve open, and means for preventing the operation of said valve holding means.

6. In a stereotype plate casting machine, the combination of mold filling devices, a shaft, an arm fixed on said shaft, a lever loose on the shaft, means for transmitting power to the shaft, and a pin connecting said arm and lever and having a reduced cross-section adapted to break in case of obstruction before any other part of the machine is injured.

In testimony whereof I have hereunto set my hand.

HENRY A. WISE WOOD.
